UNITED STATES PATENT OFFICE.

ALFRED L. COBB, OF BOULDER, COLORADO, ASSIGNOR OF ONE-HALF TO
JAMES COWIE, OF SAME PLACE.

LIFTING-JACK.

SPECIFICATION forming part of Letters Patent No. 657,514, dated September 11, 1900.

Application filed June 4, 1900. Serial No. 19,021. (No model.)

To all whom it may concern:

Be it known that I, ALFRED L. COBB, a citizen of the United States, residing at Boulder, in the county of Boulder and State of Colorado, have invented a new and useful Lifting-Jack, of which the following is a specification.

The invention relates to improvements in lifting-jacks.

The objects of the present invention are to improve the construction of lifting-jacks and to provide a simple and inexpensive and efficient one of that class which employs a screw and to enable the latter to be readily rotated independently of the supporting head or portion and to exclude dust effectually from the bearings.

The invention consists in the construction and novel combination and arrangement of parts hereinafter fully described, illustrated in the accompanying drawings, and pointed out in the claims hereto appended.

In the drawings, Figure 1 is a vertical sectional view of a lifting-jack constructed in accordance with this invention. Fig. 2 is a detail perspective view of the upper portion of the screw. Fig. 3 is a similar view of the supporting head or cap, the same being inverted. Fig. 4 is a detail view of the securing-nut, showing the same inverted.

Like numerals of reference designate corresponding parts in all the figures of the drawings.

1 designates a tubular standard provided with an interiorly-threaded upper portion 2, forming a fixed nut and receiving a jack-screw 3, which is provided at its upper end with a rounded enlargement 4, adapted to be engaged by a bar or lever for rotating the screw. The rounded enlargement 4, which extends outward beyond the edges of the top of the tubular standard, is provided with horizontal transverse openings 5, arranged at right angles to each other and adapted to receive the actuating bar or lever.

The upper face of the cylindrical enlargement 4 is provided with an annular groove 6, extending around a vertical stud 7 and forming a ball-race for the reception of a series of antifriction-balls 8, which are interposed between the upper face of the cylindrical enlargement and the lower face of a support-

ing cap or head 9. The cap or head, which is cylindrical, is provided with a central opening, and it has an annular groove 10 at its lower face for the reception of the antifriction-balls 8. The bottom of the supporting cap or head is provided at its periphery with a depending flange 11, extending below the upper face of the cylindrical enlargement 4 to provide a shield for excluding dust from the adjacent ball-bearings.

The stud 7, which is formed integral with the enlargement of the screw, is provided with a smooth lower portion 12 and an upper threaded portion 13. The smooth portion fits within the lower portion of the aperture or central opening of the supporting head or cap 9, and it forms a stem around which the latter rotates. The upper portion of the aperture of the cap or head is enlarged at a point below the threaded portion 13 of the stud to form a shoulder 14, which is provided with an annular groove to form a ball-race for the reception of an annular series of antifriction-balls 15 of less diameter than the lower balls 8 and interposed between the said shoulder and a securing-nut 16. The extreme upper portion of the aperture of the supporting head or cap is flared at 17 to receive an enlargement or projecting portion 18 of the securing-nut 16, which is located wholly beneath the upper face of the supporting head or collar, as clearly illustrated in Fig. 1 of the accompanying drawings.

The securing-nut 16, which is provided at its top with an exterior polygonal wrench-receiving enlargement 18^a, has screw-threads 19 at the upper portion of its interior to engage the screw-threads of the stud 7, and it forms a cap for the said stud. The lower portion 20 of the interior of the securing-nut is smooth, and an annular groove 21 is provided at the lower edge of the nut to receive the upper small antifriction-balls 15, and by the arrangement of the upper and lower ball-bearings the screw may be rotated freely without liability of accidentally unscrewing the securing-nut. The projecting portion, which extends from the periphery of the nut to the top thereof, has an inclined lower face to agree with the flare of the top portion of the opening or aperture of the supporting

cap or head; and by this construction a dust-proof bearing is provided. The outer face of the securing-nut and the adjacent walls of the central aperture of the supporting head 5 or cap are smooth, and the upper face of the head or cap is grooved or corrugated to prevent it from slipping on the part to be elevated. These grooves or corrugations may be formed in any suitable manner, as will be to readily apparent.

It will be seen that the lifting-jack is simple and comparatively inexpensive in its construction, that it possesses great strength and durability, and that the jack-screw is adapted 15 to rotate freely independently of the supporting head or cap. It will also be apparent that the parts are arranged to render the ball-bearings perfectly dust-proof.

What is claimed is—

- 20 1. A lifting-jack comprising a standard, a screw engaging the standard and provided at its top with an enlargement and having a vertical stud extending centrally from the enlargement and threaded at its upper end, a supporting head or cap arranged on the enlargement of the screw and provided with a central aperture extending entirely through the head or cap and receiving the stud, the upper portion of the aperture being enlarged 25 to provide a shoulder, and a securing-nut located wholly within the upper portion of the aperture of the supporting head or cap, engaging the screw-threads of the stud, and having its lower edge located directly above the said shoulder, whereby the cap or head is retained in position, said nut being provided at its upper face with a wrench-receiving enlargement located within the central aperture of the head or cap, substantially as de- 30 scribed.
2. A lifting-jack comprising a standard, a screw having an enlargement, a vertical stud projecting from the said enlargement at the top thereof and provided with a threaded up- 35 per portion and a smooth lower portion, a supporting head or cap arranged on the stud

and having a central aperture to receive the same, the upper portion of the aperture being enlarged to provide a shoulder, and the latter having an annular groove forming a ball-race, a securing-nut located within the upper portion of the aperture and having an interiorly-threaded upper portion to engage the screw-threads of the stud, the lower portion of the nut being smooth and the bottom 55 of the nut being provided with an annular groove located above the said groove, anti-friction-balls arranged in the said grooves and interposed between the shoulder of the cap or head and the lower edge of the securing-nut, and antifriction devices interposed between the cap or head and the enlargement of the screw, substantially as described.

3. A lifting-jack comprising a standard, a jack-screw engaging the standard and having a cylindrical enlargement, a vertical stud extending from the top of the enlargement and provided with a threaded upper portion and a smooth lower portion, a supporting head or cap having a central aperture receiving the stud, enlarged to form a shoulder and provided with a flaring upper portion, said shoulder being grooved, a nut fitting over and engaging the threaded portion of the stud and having an annular groove at its bottom 70 and provided at its top with a projecting peripheral portion having an inclined lower face conforming to the configuration of the flare of the aperture of the head or cap, balls interposed between the nut and the shoulder, 75 and antifriction devices arranged between the enlargement of the screw and the bottom of the head or cap, substantially as described.

In testimony that I claim the foregoing as my own I have hereto affixed my signature in the presence of two witnesses.

ALFRED L. COBB.
